(57) CLAIM

The ornamental design for a table organizer assembly as shown and described.

DESCRIPTION

FIG. 1 is a perspective view of a table organizer assembly showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a pair of side organizers removed from the table organizer assembly and placed in an alternate position.

The broken lines in the drawings depict portions of the table organizer assembly and form no part of the claim.

1 Claim, 8 Drawing Sheets
